CLAIM

The ornamental design for a power charging station, as shown and described.

DESCRIPTION

FIG. 1 is a front, top, right-hand side perspective view of a power charging station, showing our new design, shown in a first position of use;

FIG. 2 is a front, top, right-hand side perspective view thereof, shown in a second position of use;

FIG. 3 is a front view of FIG. 1;

FIG. 4 is a rear view of FIG. 1;

FIG. 5 is a right-hand side view thereof, left-hand side view being a mirror image thereof;

FIG. 6 is a top view thereof; and,

FIG. 7 is a bottom view thereof.

The broken lines are included to show portions of the power charging station that form no part of the claimed design.

1 Claim, 3 Drawing Sheets
